UNITED STATES PATENT OFFICE.

GERRET BRINK AND HERMAN BRINK, OF HUDSONVILLE, MICHIGAN.

ARTIFICIAL-STONE FENCE-POST.

No. 830,962.

Specification of Letters Patent.

Patented Sept. 11, 1906.

Application filed April 17, 1906. Serial No. 312,282.

To all whom it may concern:

Be it known that we, GERRET BRINK and HERMAN BRINK, citizens of the United States, residing at Hudsonville, in the county of Ottawa and State of Michigan, have invented new and useful Improvements in Artificial-Stone Fence-Posts, of which the following is a specification.

Our invention relates to artificial-stone fence-posts; and its primary object is to provide a novel and highly useful means for securing the line-wires of a fence to the post.

A further object of the invention is to provide line-wire-attaching means which may be applied readily and quickly, which is simple and durable, and which may be manufactured and sold at a comparatively low cost.

With the above and other objects in view the invention consists in the construction, combination, and arrangement of parts hereinafter fully described, claimed, and illustrated in the accompanying drawings, wherein—

Figure 1 is a perspective view of a fence-post, illustrating the manner in which the line-wires are secured to the post by our improved line-wire-attaching means. Fig. 2 is a central longitudinal sectional view through the post. Fig. 3 is an enlarged sectional view of a fragmentary portion of the fence-post, and Fig. 4 is a transverse sectional view on the line 4 4 of Fig. 3.

Referring to the drawings by reference-numerals, 1 designates a fence-post which is constructed of any plastic material suitable for the purpose and which is of a size and shape to best adapt it to answer the requirements demanded of a suitable fence-post. Embedded in and extending longitudinally through the post are strengthening-wires 2, which are arranged at points adjacent the corners of the post and which are adapted to prevent injury to the post.

3 designates line-wire-supporting members which also are embedded in the post and which are constructed of single strands of wire bent upon themselves into U shape, as fully disclosed in Fig. 4 of the drawings. The looped ends of the supporting members 3 extend beyond the outer face of the post 1, and the line-wires 4 of a fence are positioned upon and secured to the projecting ends of the members 3.

5 designates the line-wire-attaching members, which also are constructed of single

strands of wire bent into U shape, as fully disclosed in Fig. 3 of the drawings. The attaching members 5 are applied to straddle the line-wires 4 and to position their vertical portions 6 between the line-wires and the face 60 of the post and their vertical portions 7 between the closed ends of the supporting members 3 and the line-wires, as is fully illustrated in Fig. 3 of the drawings. After the attaching members have been thus applied 65 those portions of their vertical members 7 which extend below the supporting members 3 are turned upwardly over the closed ends of the members 3 and engaged with the face of the post 1, thus securely locking the attaching members 5 in applied position and in turn securing the line-wires 4 in position upon the post.

It should be apparent from the above description, taken in connection with the accompanying drawings, that we provide a line-wire-attaching means which has such connection with supporting members carried by the post and the line-wires that all liability of the attaching means becoming accidentally disengaged from the supporting members is obviated. It also should be apparent that the line-wire-attaching means is exceedingly cheap of construction, that it may be readily and quickly applied without 85 the use of any special tools, and that it may be manufactured and sold at a comparatively low cost.

Having fully described and illustrated our invention, what we claim is—

1. The combination with a fence-post, of a supporting member secured to the post, a line-wire supported by said member, and a U-shaped attaching member applied to straddle the wire and position one of its vertical portions between the post and the wire and its other vertical portion between the wire and the supporting member, that vertical portion positioned between the wire and the supporting member being bent upwardly to 95 engage said supporting member to lock the attaching member in applied position.

2. The combination with a fence-post, of a U-shaped member secured to and having its closed end projected beyond the post, a line-wire supported by said member, and a U-shaped attaching member applied to straddle the wire and position one of its vertical portions within the supporting member and between the wire and the post and its other 100 105 110

vertical portion within the supporting member and between the wire and the closed end of said supporting member, that vertical portion positioned between the wire and said 5 closed end being bent upwardly to engage the supporting member and the post to lock the attaching member in applied position.

In testimony whereof we affix our signatures in presence of two witnesses.

GERRET BRINK.
HERMAN BRINK.
